UNITED STATES PATENT OFFICE.

CHARLES H. EDDY, OF ATTLEBORO, MASSACHUSETTS.

TOBACCO AND MATCH POUCH.

1,193,371.

Specification of Letters Patent. Patented Aug. 1, 1916.

Application filed May 3, 1915. Serial No. 25,475.

To all whom it may concern:

Be it known that I, CHARLES H. EDDY, a citizen of the United States, residing at Attleboro, in the county of Bristol, in the 5 State of Massachusetts, have invented a certain new and useful Improvement in Tobacco and Match Pouches, of which the following is a specification, reference being had to the accompanying drawings.

10 The object of this invention is to provide a specially convenient, and reasonably cheap, pouch or container for "cut" or granular tobacco, including means for agitating the mass of tobacco in the event that it becomes 15 caked, also for discharging a "pipe-full" of said tobacco through a closable discharge opening, and my said device also includes a receptacle for matches; all being contained in a case which is preferably formed of 20 metal and is so shaped and sized that it may be conveniently carried in the pocket of the user.

The annexed drawing illustrates my improved pouch, Figure 1 being a side view of 25 the same, approximately full size, and Fig. 2 is a central, vertical, sectional view of the same. Fig. 3 is a lower end view of the pouch. Fig. 4 is a transverse sectional view taken on line 4—4 of Fig. 1 and Fig. 5 is a 30 like view taken on the line 5—5 of said Fig. 1.

Referring to these drawings, the reference letter *a* indicates the pouch proper, the same being preferably, of sheet metal or the like 35 substantial material. Said pouch is shaped, in transverse section, as an elongated oval and the lower portion is formed with an opening *b* which is normally closed by a hinged gate *c*.

40 The upper, central, portion of the pouch is notched as at *d* to receive, and protect, a valve-rod *e* which is slidably mounted in the pouch and carries at its lower end (within the pouch) a plunger disk *f* which is normally located an inch or so above the discharge opening *b*, the arrangement being 45 such that, when the rod *e* is forced down-

ward, the plunger disk *f* will operate to stir up and separate the grains of tobacco and will force a certain quantity of the tobacco 50 out through the opening *b*. At one side of the notch *d* I provide a partition *g* thus providing a match receptacle which has a spring-controlled cover *h*. At the other side of said notch I have mounted a spring- 55 controlled cover *i* which serves as a closure for the opening *k* through which the pouch may be conveniently filled with tobacco.

When it is desired to use my described pouch, and assuming that it has been filled 60 with granulated tobacco, the gate *c* is swung to one side to open the discharge hole *b*. If the tobacco has become caked or clogged, the rod *e* is pushed down, against the force of a spring *m* thus causing the plunger disk 65 *f* to stir up the tobacco and to force a certain quantity through the said discharge opening, into a pipe, or cigarette paper, or into the hand of the user of the pouch. The gate *c* is then swung to its closed position. 70 When the pipe or cigarette is ready to be lighted, the lid *h* is raised and a match is taken from the match-box.

The thin form of the pouch makes it 75 specially convenient for carrying in one's pocket, and the notched upper end of said pouch provides a protective chamber for the location of the plunger *e*.

Having thus described my invention, I claim as new and wish to secure by Letters 80 Patent:—

A pouch, whose body portion is of an inflexible character, having a depression in its upper end portion and a closure controlled discharge opening in its bottom, and a 85 plunger whose head is arranged to be normally suspended in elevated position within said pouch body portion, in alinement with said closure controlled opening, said plunger having its upper actuating end received 90 within said depression and equipped therein with a resilient member adapted to control the position of said plunger.

CHARLES H. EDDY.
